REFRIGERATOR DOOR LOCK

Herbert D. Squire, Galesburg, Ill., assignor to Midwest Manufacturing Corporation, Galesburg, Ill.

Application October 31, 1956, Serial No. 619,517

9 Claims. (Cl. 292—219)

This invention relates to improvements in door latches and more particularly to an improved latch for holding the door closed in household refrigerators.

As is well known to those versed in the art household refrigerators are provided with various kinds of operating handles for causing the release of the latch mechanism which holds the door closed. The type of handles varies with different models, some of them being pull type for causing the release and others being of the handle and push button type. Usually the latch mechanism must be selected to suit the particular type of handle or vice versa with the result that changes in handle types often cause a considerable amount of door redesign which is relatively expensive.

By the present invention it is possible to provide a single latch mechanism which may be used with a variety of handles and/or push button releases thus reducing the number of parts that need to be stocked for manufacture or replacement.

Basically, the invention contemplates a bolt mechanism with which is associated a latch and release mechanism wherein the latch and release mechanism may be assembled in different relations to the bolt mechanism to provide the versatility mentioned.

Other advantages of the invention and the invention itself will become more apparent from the following description of an embodiment thereof, which description is illustrated by the accompanying drawings and forms a part of this specification.

In the drawings:

Fig. 1 is a horizontal section through a fragment of a door and cabinet showing a plan view of the lock and its manner of cooperation with the door and cabinet;

Fig. 2 is a view taken from the line 2—2 of Fig. 1;

Fig. 3 is a view taken from the line 3—3 of Fig. 1;

Fig. 4 is an enlarged horizontal section through the lock;

Fig. 5 is a plan view of a release cam; and

Fig. 6 is a fragmentary view similar to Fig. 4, showing a different adjustment for the release means.

As illustrated in the drawings, there is provided a main housing which comprises spaced parallel side walls 10 connected together by a bridging end wall 11. Each side wall is provided with a laterally extending flange 12 having openings 13 for the reception of screws for holding the same to a suitable frame on the door which carries the same.

Pivotedly supported between the side walls 10 of the main housing on a pivot pin 15 is a bolt housing, Figs. 2 and 4, which comprises parallel side walls 16 held in spaced relation to each other by a bridging end wall 17. Opposite to the end wall 17, tongues 18 are struck from the side walls and bent inwardly normal to the side walls the extremities being provided with spring seating lugs 19 that project toward the end wall 17. Beyond those portions the sides of the housing are provided with extending arms 20 the end of each of which carries an inwardly extending lug 22. The lugs project toward each other in a vertical plane to provide pawl engaging sur-

2

faces that are engaged by a pawl which may be released to allow the bolt housing to pivot about the pin 15. Normally the bolt housing is held in the position shown where-in the end wall 17 lies flat against the end wall 11 of the main housing by a spring 50 which is coiled about the pin 15 and has an arm 51 engaging with the wall 11 and an arm 52 engaging with a bolt pivot pin 28.

The bolt is comprised of a pair of spaced parallel members 25 connected together by a bridging portion 26. The lower portion of the bolt, as viewed in the figures, provides a pair of spaced parallel arms 27 which are journaled on a pivot pin 28 carried at the lower righthand side of the bolt housing. The upper end of the bolt is provided with a pair of spaced parallel curved extensions 30 which carry a keeper engaging roller 31. The bolt is held with the wall 26 against the inner side of the bolt housing wall 17 by a heavy helical spring 32, one end of which is seated on the arms 18 of the bolt housing and held in position by the lugs 19 while the other end of the spring is seated on a boss 33 formed by displacement of the wall 26. Thus the bolt and bolt housing are held in a predetermined fixed position but the bolt may pivot on the pin 28 relative to the bolt housing against the heavy pressure of the spring 32.

It should be pointed out that normally the bolt housing is locked against pivoting in the main housing and that the pivot point 15 for the bolt housing is inwardly of right side (Fig. 4) of the main housing and spaced from the pivot point 28 for the bolt. The pivot point 28 for the bolt is very close to a line running through the axis of the bolt roller 31 and normal to the holding surface of the keeper (see Fig. 1). Hence, when the housing is locked, the roller pressure against the keeper is normal to its holding surface and therefore the door is held securely closed. When the bolt housing is released the pressure of the spring 32 is such that the bolt and the bolt housing may be considered as one element and upon release of the housing it, along with the bolt, may pivot about the pivot 15 which is to one side of a line through the roller and the keeper surface. The pressure between the roller and the keeper now allows the housing and bolt to pivot and the roller rolls off of the keeper surface becoming disengaged therefrom.

When the door is moved to a closed position, however, the roller on the bolt engages with the slanting surface on the keeper and the heavy spring is compressed allowing the bolt to move relative to the bolt housing. It rolls up the cam surface and eventually is forced over into engagement with the keeper surface by the spring 32.

The bolt housing is normally held against pivoting by a pawl which comprises a pair of side walls 40 the lower ends of which are provided with enlarged circular portions 41 that are pivoted on a pin 42 secured in and bridging the side walls 10 of the main housing. The two side walls 55 of the pawl are bridged by a wall 43 the upper end of which extends beyond the side walls 43 at 44 and is provided with a T extension 45 beyond the confines of the main housing. At the lower end the wall 43 follows the contour of the side walls and then extends outwardly 60 tangent thereto to provide an arm 46 which extends beyond the confines of the main housing.

Pressure may be applied to the T 45 or to the arm 46 to tilt the pawl against the pressure of a spring 56 which is coiled about the pin 42 and has one arm 57 engaged in an aperture 58 in the side wall of the housing and the other end 59 engaged with the arm 46 to hold the pawl spring pressed counter-clockwise as viewed in Fig. 4.

At their upper ends, the side walls of the pawl are provided with steps 60 which underlie the pawl engaging surfaces 22 and hold the bolt housing against pivoting. When this pawl is released, and the door pulled outward, or pressed outward by spring means, the bolt

housing may pivot and the bolt is released from the keeper as previously described.

As previously stated, the arm 46 may be moved by any suitable means such as a push button, not shown, or a lever as shown in Fig. 1, or the arm 45 may be moved by suitable means to allow the pawl to be released. In addition, the pawl may be reversed and the pin 42 seated in the holes 58. When this is done, the arm 46 extends between the walls of the main housing and is accessible for operation since the walls between the flanges 12 are open. This enables a wider variety of locations for push button releases to be obtained and also allows the end 45 to be operated in the opposite direction.

Another form of release for the pawl which further increases its versatility includes a pawl release cam 70 which is a flat elongated narrow plate that is slidably journaled in elongated openings 71 in the side walls of the housing. The plate is provided with spaced notches 72 the conformation of which defines cam surfaces 73 and stops 74. The edge of the plate at the bottom of the notches 72, when the plate is in position, engages with the edges of the opening in which the release slides. When the pawl release is slid in the openings 71, the cam surfaces 73, riding on the edges causes the pawl release to move toward the pawl and engage with the upper edge surfaces 40a of the pawl to rock the pawl clockwise.

The pawl release is normally held in a position such that the stops 74 are engaged with one or both of the side walls of the housing, at which time it is in a position where the pawl is in locking engagement with the bolt housing, by a spring 80, Fig. 2, which has an offset end 81 engaged in a transversely extending opening 82 in the pawl release, the main body of the spring extending backward alongside the housing and having a bent end portion engaged in a seat 83 formed by striking a portion outwardly from the end wall 11. The pawl release is provided with openings 84 and 85 in each end through which a rod 86 may be connected for sliding the release in the housing. Thus the pawl release may be pushed or pulled to operate it. The release may also be reversed end for end, in which event the spring would be attached from the other side thus allowing a greater variety of connections to the door handle to be made.

It is to be understood that, while there has been described in detail herein and illustrated in the accompanying drawings a particular preferred embodiment of this invention, various modifications, omissions and refinements which depart from the disclosed embodiment may be adopted without departing from the spirit and scope of the present invention.

I claim:

1. In a latch mechanism adapted to engage a keeper, said latch mechanism having a housing adapted to be mounted on a support, a latch bolt carriage pivotally mounted on said housing and pivotable with respect thereto between a latching position and a released position, a latch bolt pivotally mounted on said carriage and pivotable with respect thereto about an axis parallel to and laterally displaced from the pivotal axis of said bolt carriage, and a main latch spring resiliently urging said latch bolt in a keeper engaging direction with respect to said carriage; means for releasably maintaining said bolt carriage in said latching position comprising a member pivotally mounted on said housing and pivotable with respect thereto between a carriage restraining position and a carriage releasing position on bearing means substantially removed from the pivotal axis of said bolt carriage, said member being engageable with said bolt carriage when said member is in said carriage restraining position to restrain said carriage against movement from said latching position to said releasing position, said member including a plurality of arms extending generally radially of and angularly displaced about the pivotal axis thereof, said arms being accessible from without said housing for application of forces

thereto in different directions and different locations to move said member from said carriage restraining position to said carriage releasing position.

2. The combination as specified in claim 1 wherein 5 the pivotal axis of said member is parallel to and substantially displaced from the pivotal axis of said bolt carriage.

10 3. The combination as specified in claim 1 wherein said housing includes generally parallel walls defining two pairs of openings, and a pin is provided for reception by either of said pairs of openings, said pin serving as a pivot for said member, whereby said member may be alternatively oriented on said housing and each of said arms may be acted upon by a force of alternative character to move said member from said carriage restraining position to said carriage releasing position.

15 4. The combination as specified in claim 1 wherein spring means are provided urging said bolt carriage toward said latching position.

20 5. The combination as specified in claim 1 wherein spring means are provided urging said member toward said carriage restraining position.

25 6. In combination with a latch housing, a latch bolt carriage pivotally mounted on said housing and pivotable with respect thereto between a latching position and a released position, a latch bolt pivotally mounted on said carriage and pivotable with respect thereto about an axis parallel to and laterally displaced from the pivotal axis of said bolt carriage, and a main latch spring resiliently urging said latch bolt in a keeper engaging direction with respect to said carriage; means for releasably maintaining said bolt carriage in said latching position comprising a generally L-shaped member pivotally mounted on said housing and pivotable with respect thereto between a carriage restraining position and a carriage releasing position on bearing means adjacent the bend of said L-shaped member and substantially removed from the pivotal axis of said bolt carriage, one arm of said L-shaped member being engageable with said bolt carriage when said L-shaped member is in said carriage restraining position to restrain said carriage against movement from said latching position to said releasing position, the two arms of said L-shaped member being accessible from without said housing for application of forces thereto in different directions and different locations to move said L-shaped member from said carriage restraining position to said carriage releasing position.

30 7. In combination with a latch housing, a latch bolt carriage pivotally mounted on said housing and pivotable with respect thereto between a latching position and a released position, a latch bolt pivotally mounted on said carriage and pivotable with respect thereto about an axis parallel to and laterally displaced from the pivotal axis of said bolt carriage, and a main latch spring resiliently urging said latch bolt in a keeper engaging direction with respect to said carriage; means for releasably maintaining said bolt carriage in said latching position comprising a member pivotally mounted on said housing and pivotable with respect thereto between a carriage restraining position and a carriage releasing position on bearing means substantially removed from the pivotal axis of said bolt carriage, said member being engageable with said bolt carriage when said member is in said carriage restraining position to restrain said carriage against movement from said latching position to said releasing position, said member including a plurality of arms extending generally radially of and angularly displaced about the pivotal axis thereof, said arms being accessible from without said housing for application of forces thereto in different directions and different locations to move said member from said carriage restraining position to said carriage releasing position, and release means for moving said member from said carriage restraining position to said carriage releasing position, said release means including a cam strip slidably

mounted within a pair of slots provided in said housing in position to engage said member, said strip having cam means on one edge thereof whereby longitudinal movement of said cam strip in one direction causes movement of said member from said carriage restraining position to said carriage releasing position, said cam strip being reversible end-to-end within said slots whereby longitudinal movement thereof in the direction opposite said one direction may effect carriage releasing movement of said member.

8. In combination with a latch housing, a latch bolt carriage pivotally mounted on said housing and pivotable with respect thereto between a latching position and a released position, a latch bolt pivotally mounted on said carriage and pivotable with respect thereto about an axis parallel to and laterally displaced from the pivotal axis of said bolt carriage, and a main latch spring resiliently urging said latch bolt in a keeper engaging direction with respect to said carriage; means for releasably maintaining said bolt carriage in said latching position comprising a member pivotally mounted on said housing and pivotable with respect thereto between a carriage restraining position and a carriage releasing position on bearing means substantially removed from the pivotal axis of said bolt carriage, said member being engageable with said bolt carriage when said member is in said carriage restraining position to restrain said carriage against movement from said latching position to said releasing position, said member including a plurality of arms extending generally radially of and angularly displaced about the pivotal axis thereof, said arms being accessible from without said housing for application of forces thereto in different directions and different locations to move said member from said carriage restraining position to said carriage releasing position, said housing having generally parallel walls defining two pairs of openings, said bearing means including

- a pin for reception by either of said pairs of openings, whereby said member may be alternatively oriented on said housing and each of said arms may be acted upon by a force of alternative character to move said member from 5 said carriage restraining position to said carriage releasing position, and release means for moving said member from said carriage restraining position to said carriage releasing position, said release means including a cam strip slidably mounted within a pair of slots provided in said housing 10 in position to engage said member, said cam strip having cam means on one edge thereof whereby longitudinal movement of said cam strip in one direction causes movement of said member from said carriage restraining position to said carriage releasing position, said cam strip 15 being reversible edge-to-edge within said slots whereby said cam strip may engage and actuate said member in either orientation of said member.
9. The combination as specified in claim 8 wherein said cam strip is also reversible end-to-end within said 20 slots whereby longitudinal movement thereof in the direction opposite said one direction may effect carriage releasing movement of said member.
